RECEPTACLE FILLING MACHINE

George H. Daniels, Westfield, N. J.

Application February 15, 1946, Serial No. 647,883

16 Claims. (Cl. 198—30)

1

The present invention relates in general to improvements in the construction and operation of receptacle filling machines, and more particularly to machines for discharging a predetermined number of freely movable articles, such as articles shaped as balls, rollers, discs and the like, into a receptacle or container therefor. Machines of this type are especially useful in the pharmaceutical field for discharging a predetermined number of medicinal tablets into a bottle or other container.

The general object of my invention is the provision of an improved machine of the character described which automatically and periodically discharges a predetermined number of freely movable articles into one or more receptacles. A further and more specific object is the provision of a receptacle filling machine in which articles of circular cross-section are automatically aligned in an edge-to-edge formation in a plurality of side-by-side raceways, and a measured number periodically and simultaneously discharged from each raceway. A further specific object is the provision of a receptacle filling machine in which the number of articles to be periodically discharged can be easily and quickly varied over a relatively wide range by a simple adjustment of the article number measuring mechanism. A further object is a receptacle filling machine in which the charge of articles from a plurality of side-by-side raceways simultaneously discharge without clogging into a common receptacle. A further object is a receptacle filling machine of the character described in which the effective width and height of all of the raceways of the machine can be simultaneously and rapidly adjusted for a relatively wide range of article widths and diameters. A further object is the provision of a receptacle filling machine of relatively low cost simple construction in which the articles are delivered from a storage point, aligned, measured in number and discharged into a receptacle substantially without exposure to the atmosphere and without handling by an operator.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which a preferred embodiment of the invention is illustrated and described.

Of the drawings:

Fig. 1 is a side elevation of a tablet bottle filling machine constructed in accordance with my invention;

Fig. 2 is a front view of the machine;

Fig. 3 is a plan view of the machine;

Fig. 4 is an enlarged broken view in section of a portion of the machine shown in Fig. 1;

Fig. 4a is a further enlargement of a portion of the apparatus shown in Fig. 4;

2

Fig. 5 is a side elevation of one of the stop member adjusting devices;

Fig. 6 is a section on the line 6—6 of Fig. 5;

Fig. 7 is a view taken on the line 7—7 of Fig. 6;

Fig. 8 is a vertical section on the line 8—8 of Fig. 3;

Fig. 9 is an enlarged transverse section on the line 9—9 of Fig. 1;

Figs. 10 and 11 are enlarged transverse sections on the lines 10—10 and 11—11 respectively of Fig. 3;

Fig. 12 is an enlarged broken plan view of a portion of Fig. 3 with the adjustable raceway bars in a different position; and

Fig. 13 is an enlarged fragmentary section on the line 13—13 of Fig. 12.

In the drawings, my invention is illustrated as embodied in a machine for discharging predetermined numbers of medicinal tablets having flat or rounded sides into bottles, a field of use for which the machine of my invention is especially adapted because of the close control of medicinal tablet quantities required by statute.

The receptacle filling machine illustrated consists of three main sections, (1) an upper tablet feeding and aligning section in which tablets from a supply container are vibrated until in edge-to-edge contact in a series of separate feed channels, (2) an intermediate tablet measuring section in which a predetermined number of tablets are periodically and simultaneously segregated in each of a series of side-by-side raceways communicating with the feed channels in the feeding and aligning section and periodically discharged simultaneously, and (3) a lower tablet discharge section in which the tablets from a group of raceways are simultaneously discharged into a common receptacle.

As shown in Figs. 1, 2, 3, 10 and 11, the tablet feeding and aligning section is formed by an electro-magnetic vibrator unit 15 of any suitable form having an inclined shallow vibrating pan 16 open at its lower end. The pan 16 contains a replaceable molded or cast trough member 17 divided by longitudinally extending parallel vertical partitions 18 into a series of side-by-side feed channels 19. The uppermost section of the pan has a raised floor portion 16' at the level of the top of the channels 19 and located below a transversely elongated hopper 20 divided by vertical division plates 21 into a plurality of sections 22, each delivering to a separate group of feed channels 19. The hopper sections receive a supply of tablets from a suitable storage bin, traveling belt conveyor, or grill vibrator unit thereabove (not shown) and are kept substantially full to insure an ample supply of tablets to the channels 19 at all times. The hopper is pivoted at its rear end on the pan 16, as indicated at 24, and has its forward end adjustably held above the raised section of the pan by spring clamps 25 a predetermined distance sufficient to permit a single layer of tablets to move thereunder when on their sides as the pan is vibrated. In the machine

shown, twenty feed channels 19 are employed, with the hopper 20 divided into four sections, each delivering tablets 23 to five feed channels.

The upper end section of the partitions 18 have oppositely beveled sides converging to a peak, as shown in Figs. 3 and 11, and as the tablets move on their sides off the raised pan section 16' by the vibratory effect, the tablets pass onto the beveled side section of the partitions 18 and are automatically turned upright, i. e., on their circular edges, in the feed channels 19 by the continued vibration and beveled surfaces, as indicated in Fig. 11. The channels are proportioned in width to provide a slight clearance, such as $\frac{1}{16}$ ", between the sides of the tablets and the adjacent vertical partition sides to permit free movement of the tablets in the inclined channels in edge-to-edge alignment and yet prevent any overlapping of tablets which would tend to clog the feed channels. Other forms of trough members 17 with different widths of feed channels may be easily and quickly substituted in the vibrator pan for that shown to fit other tablet thicknesses. The lower end section of the partitions 18 have parallel sides, as shown in Fig. 10. A flat transparent plate 26 rests on and forms the top of the lowermost section of the feed channels, leaving sufficient top clearance to permit free movement of a single row of tablets in each channel under the vibratory action, while a removable transparent box member 27 fits over the remaining portion of the trough member to prevent exposure of the tablets to the atmosphere. Any tablets accidentally carried down on their sides on top of the partitions 18 will be blocked by the plate 26 from further movement in that position. The supply of tablets to the channels 19 is controlled by the operator by regulating the vibratory effect in any suitable manner, such as by controlling the vibrator frequency.

The intermediate tablet measuring section is formed with a stationary base plate 30 mounted on a supporting framework 31 at a greater inclination than the trough channels, an inclination of about 30° to the horizontal being suitable, for example. Floor plate sections 32 are secured to the base plate in longitudinally spaced relation to form four upwardly tapering transverse slots 33 therebetween in which corresponding inverted U-shaped adjusting bars 34 and 35 are slideably movable transversely of the base plate. The slots 33 and bars 34 and 35 are arranged in pairs spaced longitudinally of the base plate. Adjusting screws 36 and 37 mounted in stationary side bars 38 at opposite sides of the base plate 30 are operatively connected to one end of the bars 34 and 35 respectively, the screws 36 being at one side of the machine and the screws 37 at the opposite side. The adjusting bars 34 and 35 are connected to corresponding alternate longitudinally extending parallel raceway-forming bars 40 and 41 respectively by screws 42, the bars 40 and 41 of adjacent pairs forming a tablet raceway 43 therebetween and being movable towards and away from each other by the corresponding adjusting screws to vary the width of the raceways 43 to fit tablets of a particular thickness with a predetermined side clearance, permitting the tablets to freely roll down the raceways and yet preventing any overlapping which might tend to clog the raceways. The tablet feeding and aligning section of the machine is detachably connected to the intermediate section, as by guide pins 45, to have

the lower ends of the feed channels 19 therein register with the upper ends of corresponding raceways 43 in the intermediate section.

The bars 40 and 41 are shown in Figs. 3 and 9 in the maximum raceway width position, the bars 40 being moved to the right by the adjusting bars 34 and the bars 41 towards the left by the adjusting bars 35, as seen in Fig. 9, to decrease the width of the raceways 43, such as 10 to the position indicated in Figs. 12 and 13, when tablets of lesser thickness are to be handled. A range of tablet thicknesses of $\frac{3}{32}$ " to $\frac{15}{64}$ " is permissible, for example. The outer sides of the outermost raceways 43 are defined by inverted channel members 46 and 47 adjacent the stationary bars 38, the channel 46 being secured to and movable with the adjusting bars 34 and the channel 47 similarly connected to the adjusting bars 35, by screws 50. The adjusting screws 36 and 37 abut the outer legs of the channels 46 and 47 respectively and thereby actuate the corresponding bars 34 and 35 inwardly. The channels 46 and 47 are also resiliently connected to the adjacent stationary side bars 38 by spaced bolts 48 extending through the outer leg of the corresponding channel bar and carrying springs 49 thereon which move the adjusting bars laterally when the adjusting screws are turned to permit an increase in the raceway width.

30 A removable transparent cover plate 52 having a series of short parallel depending ribs 53 extending longitudinally of its underside is resiliently supported over the intermediate tablet measuring section at its sides by springs 55 on projecting bolts 54, the plate position being adjustable by thumb nuts 56. Adjacent ribs 53 are transversely spaced a distance corresponding to the centerline spacing of the raceways 43, so that by adjustment of the nuts 56 the effective height of the tablet raceways 43 can be regulated. Preferably the raceway height defined by the bottoms of the ribs 53 will permit a slight clearance over the tablet diameter, permitting free movement of the tablets but preventing any deviation from the edge-to-edge tablet formation in the raceways. The cover plate is thus quickly removable to permit cleaning of the raceways.

50 In accordance with my invention, mechanism is provided for segregating a corresponding number of tablets in each raceway and discharging the batches of segregated tablets simultaneously from all of the raceways. For this purpose, the base plate 30 and floor plate sections 32 have 55 transverse rows of registering stop pin openings 60 along the centerline of the raceways, the rows of openings being longitudinally spaced to segregate variable quantities of tablets of different diameters. The machine illustrated is adapted 60 to segregate 5 to 25 tablets, ranging in diameter from $\frac{1}{4}$ " to $\frac{1}{2}$ ", in each raceway, for example. A pair of cross-bars 61 and 62 are provided below the base plate, the upper cross-bar 61 carrying a series of stop pins 63 and the lower cross-bar 65 62 carrying a series of stop pins 64. The pins 63 and 64 are mounted in holes 66 in the cross-bars and held in position by screws 66 which permit regulation of the extent of projection of the pins through the corresponding openings 60 into the raceways. The cross-bar 62 is normally located below the lowermost row of stop pin openings 60 and the cross-bar 61 below the row of openings 60 which will permit a predetermined 70 number of tablets in the portion of each race-

way between the two rows of openings 60 then occupied by the stop pins 63 and 64.

The cross-bars 61 and 62 are resiliently supported by horizontal extension arms 68 projecting through vertically elongated slots 69 in the inner side of pairs of traveling carriages 70 at opposite sides of the machine. A pair of vertical flanges 75 extend outwardly on each carriage along the sides of the slot 69. The carriages 70 are slideably mounted in U-shaped rails 72 extending along the sides of the machine. Each cross-bar arm, as shown in Figs. 5-7, is resiliently supported on a spring 73 carried on a bolt 74, threaded through the arm and slideably extending through the bottom flange 77 of the carriage flanges 75, the spring 73 abutting the carriage bottom flange and underside of the extension arm. When the cross-bar 61 or 62 is to be moved to a new row of stop pin openings, the operator presses down on thumb nuts 76 on the upper ends of the bolts 74, depressing the cross-bar against the action of the springs 73 until the corresponding stop pins are below the base plate 30. The pair of opposite carriages 70 are then simultaneously slid along the rails 72 to the desired new position.

The mechanism for vertically reciprocating the stop pins 63 and 64 in the corresponding set of openings 60 consists of a cam 80 having bearing portions 79 rotatably mounted in the flanges 75 of each carriage 70 at the outer sides of the bolts 74 and arranged to actuate the corresponding extension bar 68, the cam bearing portions 79 being provided with square openings through which a square operating shaft 82 at each side of the machine extends, so that the carriage and cam are slideable on the shaft. The end portions of each shaft 82 are of circular cross-section for rotation in pillow blocks 83 secured to the base plate 30. The lower ends of the shafts carry bevel gears 84 which are arranged to mesh with oppositely arranged bevel gears 85 and 86 on a transverse drive shaft 88 driven by an electric motor 89 through suitable speed reducing mechanism, as indicated in Fig. 1. The shafts 82 thus rotate in opposite directions as indicated and the transversely opposite cams 80 are oppositely arranged, providing a uniform vertical reciprocating movement of each cross-bar throughout its length and the stop pins thereon. The pair of cams on each shaft 82 are of similar shape and angularly spaced 180° thereon, so that when the stop pins 63 are in their lowermost or retracted position, i. e., flush with or slightly below the bottoms of the raceways, the stop pins 64 are in their uppermost or raised position, i. e., about at the center line of the tablets, and vice versa. Such a degree of projection provides an effective stop for the tablets, yet avoids any tendency to rupture the same. Each cross-bar is provided with spaced adjusting screw stops 90 which are arranged to contact with the bottom of the base plate when the cross-bar is raised and limit the amount of projection of the stop pins into the raceways. This adjustment is advantageous for different tablet diameters. The curved surfaces of the cams are proportioned to effect a short dwell in the raised position, a gradual descending movement, a long dwell in the low position, and a rapid return of the stop pins 70 to the raised position.

When the described mechanism is put into operation, the vibrator is first run with the stop pins 64 in their raised position and the pins 63 flush with the bottom of the raceways, permitting 75

a free flow of tablets through the registering feed channels 19 and raceways 43 until the raceways are filled. The measuring and discharge mechanism is then ready to operate. The motor 89 is 5 then started, operating the shafts 82 to actuate the cams and stop pin mechanism, raising the stop pins 63 to cut off the flow of tablets above that level and then lowering the stop pins 64 to allow the charge of tablets of a predetermined 10 number depending upon the location of the row of openings 60 occupied by the pins 63, to simultaneously discharge from the lower end of all of the raceways. The motor speed is regulated 15 so that when the raceway section between the upper and lower stop pin locations is cleared, the pins 64 will rise into the raceway and the pins 63 descend to permit a new charge of tablets to flow into the tablet measuring section. The raceway and feed channel lengths are proportioned to provide an ample tablet storage space, 20 insuring a full charge of tablets into the measuring section during the period while the pins 63 are retracted and a substantially continuous flow of tablets into the feed channels. As shown in 25 Figs. 4 and 4a, a relatively large number of rows of stop pin openings 60 are provided to permit adjustment of the machine to handle a relatively wide range of tablet diameters in charges ranging in number in each raceway. For example, 30 the machine illustrated is designed to discharge tablets in sizes $\frac{1}{4}$ " to $\frac{1}{2}$ " in diameter in batches of 5, 6, 20 or 25 tablets in each raceway. The free 35 flow of tablets without danger of clogging the raceways, afforded by the permissible adjustment for changes in tablet thickness and diameter, permits a rapid cycle of tablet loading and discharge periods to be maintained, such as 9 cycles per minute, for example.

The machine is provided with a tablet discharge 40 section constructed to permit a plurality of raceways to discharge simultaneously into a common receptacle, such as one of a row of tablet bottles 92 held in a master block or conveyor 93. Each bottle is positioned below the lower end of a 45 corresponding funnel 94 carried by a frame 95 which is vertically adjustable on the machine supporting structure 31. As shown in Figs. 1-4 and 8, the lowermost floor plate section 32 has a series of pairs of downwardly converging guide 50 plates 96 thereon, each pair of guide plates extending across the discharge end of a plurality of raceways 43 and having the space between 55 their lower ends registering with an opening 97 in the side of a corresponding cylindrical funnel 99 above the mouth of a corresponding subjacent funnel 94. A removable transparent cover plate 100 extends over the guide plates 96 and funnels 99 to minimize exposure of the tablets to the atmosphere.

In the machine shown, groups of five raceways 60 are illustrated as simultaneously discharging into each bottle 92. I have found that five converging streams of tablets tend to clog the relatively restricted opening 97 into the funnel 99. To eliminate this tendency and to maintain a free uninterrupted tablet flow into the bottles, I have provided a downwardly tapering gradually thickening section 102 on the upper surface of the floor plate section with its upper end opposite the three center raceways of each group of five. This forms in effect a ski jump for these three rows of tablets and as a result appears to raise these tablets sufficiently above the two outer rows of tablets that there is no interference between the tablets entering the opening 97 sufficient to cause

clogging. Rapid filling of the bottles is effected in one or more cycles of the machine, depending upon the desired number of tablets to be inserted, and the filled bottles are then replaced by a new set of bottles manually or mechanically without interrupting the operating cycle.

While in accordance with the provisions of the statutes I have illustrated and described herein the best form of the invention now known to me, those skilled in the art will understand that changes may be made in the form of the apparatus disclosed without departing from the spirit of the invention covered by my claims, and that certain features of the invention may sometimes be used to advantage without a corresponding use of other features. While the machine has been specifically described and is especially useful for handling articles of circular cross-section, it can also be used for other freely movable articles, such as capsules, which will slide down the raceways, for example.

I claim:

1. An article handling machine comprising a measuring section including a plurality of side-by-side inclined stationary raceways arranged to receive rows of freely movable articles and means for periodically segregating in and subsequently gravitationally discharging all of a predetermined group of said articles simultaneously from each of said raceways, and a discharge section including stationary guide means for directing the articles discharged from a plurality of groups of raceways to corresponding common discharge openings.

2. An article handling machine comprising a feeding and aligning section including means for feeding and aligning freely movable articles in rows in a plurality of side-by-side feed channels, an intermediate measuring section including a plurality of side-by-side inclined stationary raceways arranged to receive rows of articles from corresponding feed channels and means for periodically segregating in and subsequently gravitationally discharging all of a predetermined group of said articles simultaneously from each of said raceways, and a discharge section including stationary guide means for directing the articles discharged from a plurality of groups of raceways to corresponding common discharge openings.

3. An article handling machine comprising a floor, a series of raceway-forming bars arranged in pairs on said floor to form stationary raceways therebetween for rows of articles, and a transversely movable bar supporting member arranged for relatively moving said raceway-forming bars in transversely opposite directions to vary the width of said raceways.

4. An article handling machine comprising an inclined floor, a series of raceway-forming bars arranged in pairs on said floor to form inclined stationary raceways therebetween for rows of articles, a transverse adjusting bar secured to one of the raceway-forming bars of each pair, a second transverse adjusting bar secured to the other raceway-forming bar of each pair, and means for transversely moving said adjusting bars in opposite directions to vary the width of said raceways.

5. An article handling machine comprising an inclined floor having longitudinally spaced transversely extending slots therein, a series of raceway-forming bars arranged in pairs on said floor to form inclined raceways therebetween for rows of articles, a pair of longitudinally spaced trans-

verse adjusting bars in said slots secured to one of the raceway-forming bars of each pair, a second pair of longitudinally spaced transverse adjusting bars in said slots secured to the other raceway-forming bar of each pair, and means for transversely moving said adjusting bars in opposite directions to vary the width of said raceways.

6. An article handling machine comprising a floor, a series of raceway-forming bars on said floor arranged in pairs to form raceways therebetween on said floor for rows of articles, a frame having depending members extending downwardly between corresponding pairs of raceway-forming bars and defining the height of said raceways, and means for varying the position of said frame to correspondingly vary the effective height of said raceways.

7. An article handling machine comprising an inclined floor, a series of raceway-forming bars arranged in pairs on said floor to form inclined raceways therebetween for rows of articles, means for transversely moving said raceway-forming bars in opposite directions to vary the width of said raceways, a cover plate having depending members above each raceway and defining the height of said raceways, and means for varying the position of said cover plate to correspondingly vary the effective height of said raceways.

8. An article handling machine comprising an inclined floor, a series of raceway-forming bars arranged in pairs on said floor to form inclined raceways therebetween for rows of articles, a transverse adjusting bar secured to one of the raceway-forming bars of each plate, a second transverse adjusting bar secured to the other raceway-forming bar of each pair, means for transversely moving said adjusting bars in opposite directions to vary the width of said raceways, a cover plate having depending members above each raceway and defining the height of said raceways, and means for varying the position of said cover plate to correspondingly vary the effective height of said raceways.

9. An article handling machine comprising an inclined floor, means arranged to form a series of inclined side-by-side raceways on said floor, means for supplying a row of articles to each of said raceways, upper and lower transverse rows of floor openings spaced longitudinally in said raceways, upper and lower transverse rows of stop pins arranged for reciprocation in said upper and lower rows of floor openings respectively normal to the angle of inclination of said raceways, and means for alternately raising and lowering said upper and lower rows of stop pins to periodically segregate and discharge a predetermined number of articles from all of said raceways simultaneously including transversely extending bars arranged to hold the stop pins in said rows normal to the angle of inclination of said raceways.

10. An article handling machine comprising an inclined floor, means arranged to form a series of inclined side-by-side raceways on said floor, means for supplying a row of articles to each of said raceways, upper and lower transverse rows of floor openings spaced longitudinally in said raceways, upper and lower transverse rows of stop pins arranged for reciprocation in said upper and lower rows of floor openings respectively, and means for alternately raising and lowering said upper and lower rows of stop pins to periodically segregate and discharge a predetermined number of articles from all of said raceways simultaneously including a cross-bar adjustably

supporting each row of stop pins, means for resiliently supporting said cross-bars, a pair of oppositely arranged cams arranged to vertically reciprocate each cross-bar, and means for rotating said cams in opposite directions.

11. An article handling machine comprising an inclined floor, means arranged to form a series of inclined side-by-side raceways on said floor, means for supplying a row of articles to each of said raceways, upper and lower transverse rows of floor openings spaced longitudinally in said raceways upper and lower transverse rows of stop pins arranged for reciprocation in said upper and lower rows of floor openings respectively normal to the angle of inclination of said raceways, means for alternately raising and lowering said upper and lower rows of stop pins to periodically segregate and discharge a predetermined number of articles from all of said raceways simultaneously including transversely extending bars arranged to hold the stop pins in said rows normal to the angle of inclination of said raceways, and means for adjustably limiting the projection of said rows of stop pins into said raceways.

12. An article handling machine comprising an inclined floor, means arranged to form a series of inclined side-by-side raceways on said floor, means for supplying a row of articles to each of said raceways, upper and lower transverse rows of floor openings spaced longitudinally in said raceways, upper and lower transverse rows of stop pins arranged for reciprocation in said upper and lower rows of floor openings respectively, means for alternately raising and lowering said upper and lower rows of stop pins to periodically segregate and discharge a predetermined number of articles from all of said raceways simultaneously, and means for shifting the position of at least one of said rows of stop pins longitudinally of said raceways to correspondingly vary the number of articles in each raceway simultaneously segregated and discharged.

13. An article handling machine comprising an inclined floor, means arranged to form a series of inclined side-by-side raceways on said floor, means for supplying a row of articles to each of said raceways, upper and lower transverse rows of floor openings spaced longitudinally in said raceways, upper and lower transverse rows of stop pins arranged for reciprocation in said upper and lower rows of floor openings, and means for alternately raising and lowering said upper and lower rows of stop pins to periodically segregate and discharge a predetermined number of articles from all of said raceways simultaneously including a cross-bar adjustably supporting each row of stop pins, a pair of oppositely arranged cams arranged to vertically reciprocate each cross-bar, means for rotating said cams in opposite directions, and means for shifting the position of at least one of said rows of stop pins longitudinally of said raceways to correspondingly vary the number of articles in each raceway simultaneously segregated and discharged including rails at opposite sides of said machine, and oppositely arranged carriages mounted on said rails and engaging opposite ends of one of said cross-bars.

14. An article handling machine comprising an inclined floor, means arranged to form a series of inclined side-by-side raceways on said floor, means for supplying a row of articles to each of said raceways, upper and lower transverse rows of floor openings spaced longitudinally in said raceways, upper and lower transverse rows of

stop pins arranged for reciprocation in said upper and lower rows of floor openings respectively, means for alternately raising and lowering said upper and lower rows of stop pins to periodically segregate and discharge a predetermined number of articles from all of said raceways simultaneously including a cross-bar adjustably supporting each row of stop pins, means for resiliently supporting said cross-bars, a pair of oppositely arranged cams arranged to vertically reciprocate each cross-bar, means for rotating said cams in opposite directions, and means for shifting the position of at least one of said rows of stop pins longitudinally of said raceways to correspondingly vary the number of articles in each raceway simultaneously segregated and discharged including rails at opposite sides of said machine, oppositely arranged carriages mounted on said rails and engaging opposite ends of one of said cross-bars, and means for rotatably supporting said cams in said carriages.

15. An article handling machine comprising means arranged to form a series of inclined side-by-side raceways; means for supplying a row of freely movable articles to each of said raceways, means operative through the bottom of said raceways for simultaneously obstructing the movement of said articles at a predetermined point in each of said raceways, means for simultaneously segregating a predetermined group of said articles in each of said raceways, means for shifting one of said last two named means longitudinally of said raceways, and means for alternately rendering said obstructing and segregating means effective.

16. An article handling machine comprising means arranged to form a series of inclined side-by-side raceways; means for supplying a row of freely movable articles to each of said raceways, means for simultaneously obstructing the movement of said articles at a predetermined point in each of said raceways, means operative through the bottom of said raceways for simultaneously segregating a predetermined group of said articles in each of said raceways, means for alternately rendering said obstructing and segregating means effective, and means for simultaneously varying the number of articles segregated in the groups in the several raceways.
